Primary Examiner — Jack Reickel*Assistant Examiner* — Sydney M Evans(74) *Attorney, Agent, or Firm* — Nixon & Vanderhye PC**CLAIM**

The ornamental design for a lock accessory, as shown and described.

DESCRIPTION

FIG. 1 is a front view of a lock accessory in accordance with my new design;

FIG. 2 is a rear view thereof;

FIG. 3 is a top view thereof;

FIG. 4 is a bottom view thereof;

FIG. 5 is a left side view thereof;

FIG. 6 is a right side view thereof; and,

FIG. 7 is a perspective view thereof.

The broken lines show portions of the lock accessory that form no part of the claimed design.
